DESIGN FOR A DRAIN

David S. Williams, Portland, Oreg.

Application April 4, 1936, Serial No. 61,951

Term of patent 14 years

To all whom it may concern:

Be it known that I, David S. Williams, a citizen of the United States and a resident of the city of Portland, Multnomah County, and State of Oregon, have invented a new, original, and ornamental Design for a Drain, of which the following is a specification, reference being made to the accompanying drawings which form a part thereof.

Figure 1 is a side elevational view of a drain showing my new design.

Figure 2 is a side elevation, part of which is broken away to show the under structure.

Figure 3 is a top plan view.

Figure 4 is an inverted plan view.

I claim:

The ornamental design for a drain, substantially as shown and described.

DAVID S. WILLIAMS.
